UNITED STATES PATENT OFFICE.

LUDVIG LARSEN, OF CHICAGO, ILLINOIS.

SNAP SWITCH.

1,417,751.

Specification of Letters Patent. Patented May 30, 1922.

Application filed November 28, 1919. Serial No. 341,121.

To all whom it may concern:

Be it known that I, LUDVIG LARSEN, a citizen of the United States, and a resident of the city of Chicago, in the county of Cook and State of Illinois, have invented a new and useful Improvement in Snap Switches, of which the following is a full, clear, and exact description.

My invention relates to improvements in snap switches for closing electric circuits, and it consists in the combinations, constructions and arrangements herein described and claimed.

An object of my invention is to provide a snap switch in which an oscillating switch arm, when moved in one direction, will operate to break the circuit, and when moved in the opposite direction, will close it, both the opening and the closing of the circuit being accomplished quickly by the action of one spring.

A further object of my invention is to provide a switch of the type described in which the circuit is broken at a number of different points when the switch arm is moved in one direction, and is closed at the same points when the switch arm is moved in another direction.

A further object of my invention is to provide a switch of the type described which will carry a large current, owing to numerous conducting arms, these arms being made of relatively light material.

A further object of my invention is to provide a switch which, when operated, is positively locked in position until the switch arm is moved.

Other objects and advantages will appear in the following specification, and the novel features of the invention will be particularly pointed out in the appended claims.

My invention is illustrated in the accompanying drawings, forming part of this application, in which—

Figure 1 is a side view of the device,

Figure 2 is a section along the line 2—2 of Figure 1,

Figure 3 is a section along the line 3—3 of Figure 2,

Figure 4 is a section along the line 4—4 of Figure 2, and

Figures 5, 6, 7 and 8 are detail perspective views of portions of the device,

In carrying out my invention, I provide

a U-shaped plate 1 (see Figure 1) which is made of insulating material, and which is secured by means of screws to a face plate 3.

The latter has a longitudinal opening 4, 60 as shown in the drawings. Secured to the insulating plate 1 are the spring contacts 5, 6, 7 and 8, the contacts 5 and 6 being diagonally arranged within the insulating plate 1 with respect to the contacts 7 and 6. 65

Secured to the U-shaped insulating plate 1 is a bracket 9 of the shape shown in Figure 5, which is provided with ears 10 and with openings 11 for a pivot pin 12. Disposed between the ears 10 is a yoke 13 having portions 14 provided with slots 15 (see Figure 6) arranged to receive the pivot pin 12. 70

Disposed within the yoke 13 is a contact member 16 having four contact arms 5', 6', 7' and 8'. The member 16 has aligned openings 17 arranged to receive the pivot pin 12. 75

Disposed between the ears 10 is a spring stop member 18 which is secured to the member 9 at its center. This spring stop has outwardly extending lugs 19 which are 80 arranged to enter slots 20 in the member 16.

A switch arm 21 is provided with arc shaped extending portions 22. The end of the yoke 13 is secured to the switch arm.

Disposed on the pivot pin 12 between the 85 opposed portions of the member 16 is a spacing block 23 (see Figures 2, 3 and 4). A spiral spring 24 has one end 25 arranged to bear on one side of the yoke 13, the opposite end 26 bearing on the opposite side. 90

From the foregoing description of the various parts of the device, the operation thereof may be readily understood. In Figure 1 the arms 5', 6', 7' and 8' are in engagement with their respective contacts 95 5, 6, 7 and 8. The contacts 5 and 6 are connected with a binding post 27, by means of a conductor 28, while the contacts 7 and 8 are connected with the binding post 29 by a conductor 30. The current from the 100 binding post 27 to the binding post 29 flows through the four arms. Now when the switch arm 21 in Figure 1 is pushed downwardly, it will move the end of the spring 25 (see Figure 3) with it. It will also move 105 the portion 14 of the yoke 13 until the portion 14 engages the lugs 19 of the locking spring 18 and forces them out of the slots 20. The spring 24 being under tension causes a quick throw of the member 16 bear-

ing the arms 5', 6', 7' and 8', thus breaking the circuit. When the member 16 reaches the position shown in Figure 2, the upper lugs 19 of the spring catch 18 again drop into the upper slots 20, thus locking the switch positively until the spring arm 21 is moved upwardly.

When the switch arm is moved upwardly, the end of the spring 26 is first moved, thus 10 putting the spring under tension, and the device is now unlocked, the portion 14 of the yoke disengaging the lugs 19, whereupon the arms 5', 6', 7' and 8' are snapped into engagement with their respective contacts 5, 6, 7 and 8, thus completing the circuit.

I claim:

1. A snap switch comprising an insulating casing, a face plate secured thereto and 20 being provided with an opening, a plurality of stationary contacts carried by said insulating casing, a bracket secured to said insulating casing, a switch arm pivotally mounted in said casing and adapted to oscillate in the opening of said face plate, a conducting frame pivotally mounted in said bracket and being provided with slots, said frame having arms adapted to engage said stationary contact plates, a spring stop 25 secured to said bracket and having lugs adapted to enter either of said slots in said conducting frame, a spring carried by said bracket and having its ends engaging said

switch arm and said conducting frame, and means carried by said switch arm for releasing said spring stops from the slots in said conducting frame after a predetermined movement of said switch arm, whereby said second named spring gives said conducting frame a quick throw. 35

2. A snap switch comprising an insulating casing, a face plate secured thereto and being provided with an opening, a plurality of stationary contacts carried by said insulating casing, a bracket secured to said insulating casing and carrying a pin, a switch arm pivotally mounted in said casing, adapted to oscillate in the opening of said face plate and limited by said pin in its oscillatory movement, a conducting frame pivotally 40 mounted in said bracket and being provided with slots, said frame having arms adapted to engage said stationary contact plates, a spring stop secured to said bracket and having lugs adapted to selectively engage the 45 slots in said conducting frame, a coil spring carried by said pin and having its ends engaging said switch arm and said conducting frame, a pair of lugs carried by said switch arm for releasing said spring stop 50 from the slots in said conducting frame after a predetermined movement of said switch arm, whereby said coil spring gives 55 said conducting frame a quick throw. 60

LUDVIG LARSEN.
